UNITED STATES PATENT OFFICE.

JOSEPH G. DONALDSON AND HENRY L. COLES, OF HAMILTON, OHIO, ASSIGNEES TO
GUARDIAN METALS COMPANY, OF HAMILTON, OHIO, A CORPORATION OF DELA-
WARE.

COMPOSITE STRUCTURAL UNIT.

Application filed June 29, 1923. Serial No. 648,410.

To all whom it may concern:

Be it known that we, JOSEPH G. DONALDSON and HENRY L. COLES, both citizens of the United States, and residing at Hamilton, in the county of Butler and State of Ohio, have invented certain new and useful Improvements in Composite Structural Units, of which the following is a specification.

10 The object of this invention is to provide a composite structural unit suitable for use, for example, in the construction of safes, vaults and the like, the same being of a character to resist melting or oxidation as 15 by the local application of high heat by means such as the oxy-acetylene torch, penetration by the drill, and other methods of attack and entry. It has heretofore been proposed to form a composite sheet, plate or billet (hereinafter termed a "plate") by first constructing a core of high heat resisting material and then encompassing this in metal, preferably of high heat conductivity, to facilitate the dissipation of heat throughout the mass and away from the point of attack. Our present invention involves composite material of this general character, in which, however, additional safeguards are provided against attack by any of the 20 methods above mentioned.

In carrying out our invention, we employ, imprimis, a core of high heat resistance, this being, in whole or in part, either of vitreous material or of metal or of combinations of both. Preferably such core is of such character as that when placed in a mold and the encompassing "sheath" material poured about it there will be a union of the sheath metal and the core, due to the alloying of 40 the materials of which both are composed over the contacting areas. A composite plate so formed may have a single refractory core or a plurality of such cores, and these may be arranged either in alignment or 45 staggered, as desired. Also, under this invention, the capacity of a plate so formed for resisting attack is greatly increased by combining with the internal core or cores one or more internal air-chambers suitably 50 arranged, these not only facilitating the dissipation of heat but functioning to protect the mass as against the action of explosives and the like. Heat reaching an air chamber will radiate into the air in the chamber and 55 thus become dissipated. In the event of an

explosion, gases may expand in the air chamber and thus reduce the disrupting force which would otherwise be exerted against the metal walls.

In the accompanying drawings, the four 60 figures (each of which will hereinafter be referred to in detail) illustrate cross-sections of plates constructed in accordance with this invention.

Referring first to Figure 1, this comprises first a core 1, of high heat resisting material, which may, as above stated, be of vitreous or metallic material or a combination of both. As an example of a vitreous material, we point to the use of a material included within the zirconium group, this material being preferably comminuted and melted in the presence of a suitable binder. As an example of a metallic material, we point to the use of high melting-point metals, such as tungsten, molybdenum, uranium, vanadium and the like, or combinations of one or more of these, together with nickel or copper or both, and a small quantum of carbon. As an example of a material partly vitreous and partly metallic, we point to the use of a core formed of one of the materials in the zirconium group combined with a metal such as copper, chromium and the like, serving preferably as a binder for the vitreous material and in addition tending to increase the capacity for conducting heat readily away from the point of attack. Such a core, as previously indicated, may be used singly or, where the total thickness of 90 the plate to be formed will permit, in greater number, such as two, three or four.

In practice, we prefer to mount the core or cores (as by means of chaplets) in a suitable mold and to pour around it the molten metal, such as iron, steel, copper and the like. Under this invention, however, we provide for an air-chamber or chambers within the plate, and this is accomplished by also setting up in the mold a sand or other form; suitably spaced from the core and also secured in position as by chaplets. One way by which this can be done is to encase molding sand in a suitable jacket, providing such jacket with a suitable vent 100 through which sand may, after the molding operation, be withdrawn. The jacket, which may be of any desired material, may remain a permanent part of the plate. After the core or cores and chamber form or 110

forms have been placed and secured in the mold, the molten metal may be flowed around the same, care being observed that the vent or vents for the chamber mold or 5 molds be not covered, whereupon, not only will the core or cores be rigidly and permanently united to the sheath-metal, as by alloying therewith, but provision will be made for a chamber or chambers for the purpose 10 above indicated. After the plate shall have cooled, the molding sand may be removed and the vent or vents provided therefor permanently closed by means of plugs or the like, as is well understood in the art, whereupon a plate will result having in high 15 degree the resistant qualities above mentioned. Not only may there be one or more cores, either vitreous or metallic or both, but there may also be one or more air-chambers 20 2, and such cores and chambers may be alternate throughout the mass of the plate, it being preferred, however, that the sheath material shall be of abundant mass outside of and beyond either or both the core or 25 cores and the chamber or chambers.

For the purpose of increasing the difficulty of penetration by heat attack when assisted by the fluxing rod; and also for the further purpose of increasing the difficulty 30 of attack by drill, the core or cores, whether employed in conjunction with a chamber or not, may be disposed within the mass of sheath material at an angle to the surface or surfaces thereof. The plate itself may also be set at an angle and the core or cores may or may not be parallel to the surface thereof.

Attack by means of acetylene torches, 40 when assisted by the fluxing rod, has been found most effective when a pocket can be formed in the metal—which pocket can be filled with molten iron and a jet of oxygen played thereon. Under such circumstances, the molten iron will oxidize freely, thus producing a great heat. The molten iron also 45 has a great tendency to pass into solution with the metal attacked and thus greatly assist in the disintegration or penetration thereof. However, if the plate is placed at an angle, it is difficult to form a pocket in the metal attacked, inasmuch as the molten metal dripping from the burning fluxing rod, will wash away the metal attacked in such a manner as to make it difficult to form 50 a pocket.

Such a construction is illustrated in Figure 4 and the plate may or may not be made with an air chamber or a plurality of air chambers, or with a core or plurality of cores.

Figure 3 illustrates an internal core without, however, an air chamber or chambers which, nevertheless, may be employed in this arrangement.

60 65 The sloping or inclining core will also

turn a drill sideways when the same penetrates into the plate perpendicular to the surface thereof. Also, when attack is made by a fluxing rod against such a plate, the rod has a tendency to slide along the core 70 rather than to penetrate same.

It is not essential that in employing this invention the plate, so far as concerns the sheath material, be a strictly integral mass, as it may conveniently and effectively be 75 made up of two or more sections permanently united together in any suitable manner. Such a construction is illustrated in Figure 2, in which, as will be seen, the unit is formed in three sections, 3, 4 and 5, each of these in this construction, having an internal core 1, and the core of the central section being, in this instance, angularly disposed with respect to the outermost faces of the adjacent sections 3 and 5. Also, in this instance, the central section is provided in one face with an air chamber 2 and a section 5 in one face with a similar air chamber, it being noted that in the case of the chamber first named, the bottom thereof extends at an angle relatively to the external faces of the outer sections 3 and 5, the purpose here being the same as that of angularly mounting a core or cores as explained above. In this construction, the sections may be separately cast and then, after the removal of the core material, joined into a practically integral plate, as by welding the adjoining surfaces together.

While we prefer to form the air-chamber or chambers in the sheath material, it is apparent that if desired the same may be formed in the core material, where it or they will accomplish practically the same result.

As many changes could be made in the above construction and as many different embodiments of this invention could be made without departing from the scope thereof, it is intended that all matter contained in the above description or shown in the accompanying drawings shall be interpreted as illustrative and not in a limiting sense.

Having now described our invention what we claim and desire to secure by Letters Patent is as follows:—

1. As a new article of manufacture, a core of high heat resisting material, sheath material associated therewith, and an air-chamber formed within the composite mass so constituted.

2. As a new article of manufacture, a plurality of cores of high heat resisting material, sheath material associated therewith, and an air-chamber formed within the composite mass so constituted.

3. As a new article of manufacture, a core of high heat resisting material, sheath material associated therewith, and a plurality of air-chambers formed within the composite mass so constituted.

4. As a new article of manufacture, a plurality of cores of high heat resisting material, sheath material associated therewith, and a plurality of air-chambers formed within the composite mass so constituted. 25
5. As a new article of manufacture, a core of high heat resisting material and sheath material associated therewith, said core being angularly disposed with respect to the outer face of said sheath material. 10
6. As a new article of manufacture, a core of high heat resisting material, sheath material associated therewith, and an air-chamber formed within the composite mass so constituted, a face of said chamber being angularly disposed with respect to the outer face of said sheath material. 15
7. As a new article of manufacture, a core of high heat resisting material such as an alloy of tungsten, nickel and carbon, sheath material for said core, and an air-chamber formed within the composite mass so constituted. 20
8. As a new article of manufacture, a plurality of cores of high heat resisting material such as an alloy of tungsten, nickel and carbon, sheath material for said cores, and an air-chamber formed within the composite mass so constituted. 25
9. As a new article of manufacture, a core of high heat resisting material such as an alloy of tungsten, nickel and carbon, sheath
- material for said core, and a plurality of air-chambers formed within the composite mass so constituted. 40
10. As a new article of manufacture, a plurality of cores of high heat resisting material such as an alloy of tungsten, nickel and carbon, sheath material for said cores, and a plurality of air-chambers formed within the composite mass so constituted. 45
11. As a new article of manufacture, a core of high heat resisting material and sheath material associated therewith, said plate thus formed being angularly disposed with respect to the perpendicular. 50
12. As a new article of manufacture, a plate composed of a core of high heat resisting material and sheath material associated therewith, set at an angle to the perpendicular, said plate containing an air chamber formed within the composite mass. 55
13. As a new article of manufacture, a plate composed of a core of high heat resisting material and sheath material associated therewith, set at an angle to the perpendicular, said plate containing a plurality of air chambers formed within the composite mass so constituted. 60

This specification signed this 31 day of May, 1923.

JOSEPH G. DONALDSON.
HENRY L. COLES.
